CLAIM

The ornamental design for greenhouse pot, as shown and described.

DESCRIPTION

FIG. 1 is a perspective view of a greenhouse pot in part shown from the side and bottom;

FIG. 2 is a top plan view of the greenhouse pot;

FIG. 3 is a bottom plan view of the greenhouse pot;

FIG. 4 is a right side elevational view of the greenhouse pot, the left side, front and rear elevational views are a mirror image thereof; and,

FIG. 5 is a cross sectional view taken along line 5—5 of FIG. 2.

The broken lines showing in Figures is for illustrative purposes only and form no part of the claimed design.
